US00D926793S

(12) **United States Design Patent** (10) **Patent No.:** **US D926,793 S**
(45) **Date of Patent:** **** Aug. 3, 2021**

(54) **DISPLAY PANEL OR PORTION THEREOF
WITH GRAPHICAL USER INTERFACE**

(71) Applicant: **MAGIC LEAP, INC.**, Plantation, FL (US)

(72) Inventors: **Lorena Pazmino**, Manors, FL (US); **Gregory Minh Tran**, Miami, FL (US)

(73) Assignee: **Magic Leap, Inc.**, Plantation, FL (US)

(**) Term: **15 Years**

(21) Appl. No.: **29/770,059**

(22) Filed: **Feb. 9, 2021**

Related U.S. Application Data

(63) Continuation of application No. 29/718,956, filed on Dec. 30, 2019, which is a continuation of application No. 29/635,372, filed on Jan. 30, 2018, now Pat. No. Des. 874,478.

CLAIM

The ornamental design for a display panel or portion thereof with a graphical user interface, as shown and described.

DESCRIPTION

The sole FIGURE is a front view of a display panel or portion thereof with a graphical user interface showing our design.

The outermost broken line rectangle illustrates a display panel or portion thereof that forms no part of the claimed design. The remaining broken lines illustrate portions of the graphical user interface or a mixed reality environment and form no part of the claimed design.

1 Claim, 1 Drawing Sheet
